TREATMENT OF PETROLEUM TAR ACIDS FRACTIONS

Vittorio Molinari, North Plainfield, N. J., assignor to Bakelite Corporation, a corporation of New Jersey

No Drawing. Application September 11, 1943,
Serial No. 501,991

4 Claims. (Cl. 260—627)

This invention relates to the preparation and isolation from crude tar acids of phenols suitable for reaction with formaldehyde to yield resins; these phenols comprise phenol (monohydroxy benzene) and the homologous methyl phenols which include cresols, xylenols, trimethyl phenols and tetramethyl phenols. At present it is the common practice to recover these phenols from crude tar acids produced in the high temperature carbonization of bituminous coals; and the phenols are obtained by washing the tar acids with aqueous caustic soda, separating by decanting from the oily layer the water layer carrying the phenolates in solution, concentrating the water layer to eliminate oily and pyridine impurities, and liberating the phenol mixtures by means of carbon dioxide or sulfuric acid. The mixtures of phenols are usually fractionated under vacuum into phenol, cresol and xylenol cuts, for each cut has a definite reactivity with formaldehyde.

Other large potential but unused sources of phenols for resin production are crude tar acids resulting from the cracking of petroleum. A reason for the non-use of these tar acids is the presence in them of monohydric phenols with side chains longer than the methyl, for instance, ethyl, butyl, etc., and these higher alkyl phenols show very low reactivity and interfere with or inhibit the resin-forming reactions of the much more reactive phenol and methyl phenols with formaldehyde; generally the higher alkyl phenols constitute from 5 to 10 per cent of the phenolic content, and their presence is indicated by the relatively low specific gravity of the phenol cuts compared with those of the same temperature range obtained from high temperature coal carbonization crude tar acids. Another reason for non-use is the presence in the crude tar acids of objectionable amounts of other compounds, here classed as impurities, such as neutral oil, sulfur compounds (mercaptans), nitrogen bases (pyridine), thiophenols, etc.; these impurities, and especially the sulfur compounds, are not eliminated by the usual process applied to the derivation of phenols from crude tar acids produced in high temperature coal carbonization. It is to the recovery of the useful resin-forming phenol fractions free from the higher alkyl phenols and the impurities that the present application is directed as a continuation-in-part of the copending application Serial No. 324,322 filed March 16, 1940.

It has been found that the petroleum crude tar acids can be treated to eliminate not only the higher alkyl phenols but the impurities as well by a process involving the steps:

(1) Treating the crude tar acids with aqueous caustic soda and decanting the phenolate solution from the supernatant oily layer in the usual manner; this step is the same as that for extracting crude tar acids from middle and heavy oils of high temperature coal carbonization;

(2) Heating the aqueous solutions to temperatures that cause substantial dehydration and fusion of the crude sodium phenolate, for it is essential to the effectiveness of the succeeding step that the mass be at fusion temperature; and

(3) Blowing the molten mass with a stream of air carrying a definite amount of water vapor.

The residue remaining after the blowing is dissolved in water, acidified and rectified to yield a mixture of free phenols. When the liberated phenol mixture is fractionated into phenol, cresol and xylenol cuts, the fractions have substantially the same specific gravities that characterize fractions of the same boiling range obtained by high temperature coal distillation and the same rates of reactivity with formaldehyde.

The phenolates, prepared according to step 1, are concentrated in step 2 by boiling off water and continuing the heating to the fusion temperature of the crude phenolate, generally about 280° C. and above. The blowing with air carrying a definite proportion of water vapor in step 3 is accomplished by bubbling the stream of air through water held at a fixed temperature whereby the air becomes saturated at that temperature; as a rule, bubbling through water at about 90° C. has been found to supply the amount of water required and to maintain the fused phenolate mass in the condition of concentration without becoming unduly dry and yet remain in a fused condition. An excess of air over the quantity required causes decomposition at the high fusion temperature of the useful phenol and methyl phenols, and it is accordingly necessary to stop the air flow before such decomposition begins; the amount is determined by preliminary experiments on samples of the molten mass and analyses of the results. After the step of blowing, the offensive odor, due to mercaptans or other sulfur compounds, is found to have disappeared; and either the remaining objectionable compounds are decomposed into simpler low-boiling products carried off in the air stream, or they are compounds of high boiling points remaining in the residue from which the useful phenols are readily set free.

In a German Patent No. 584,857 to Meyer the inability of purifying brown coal (lignite) tar acids by oxidation followed by steam distillation at 100° C. is explained, and the method to which

the sample of that patent is directed is first passing a cold air current through a caustic soda solution of the tar acids and then heating in an oil bath, while steam is introduced, to about 220° C. until a solid residue is formed which residue is dissolved in water and acidified to separate cresol; such a method, however, is ineffective for the treatment of petroleum tar acids. To begin with, oxidation with air at ordinary temperature of the phenolates in water solution causes no change in the objectionable higher alkyl phenols or any decrease in the impurities with the exception of the mercaptans; and oxidation with air alone of the phenolates in fused condition is not feasible on account of the energetic reaction with consequent decomposition and formation of high boiling products and tarry matter constituting a loss that may reach to 40 to 50 per cent of the original mass. In the next place steam distillation of the phenolate solution without the simultaneous passage of air has no appreciable effect as is demonstrated by the following:

Example 1.—Five thousand (5000) grams of a crude tar acids fraction, collected from petroleum-cracking products over a distillation range of from 220°-240° C., showed a specific gravity of 1.000 at 20° C. This was mixed with 1000 grams of water and 1545 grams of 98% caustic soda and then concentrated. The phenolate so formed was heated to fusion (300°-340° C.) and a stream of steam was passed through the fused mass for 3 hours. The fusion was dissolved in water, sprung with sulfuric acid and distilled under a vacuum to dryness. The bulk of the tar acids passed over in the distillation, and in all 96 per cent of the tar acids was recovered, the loss being accounted for in the transfers of the material. The specific gravity after this treatment was again 1.000 at 20° C., thus showing no change with respect to the higher alkyl phenol content.

It follows from the foregoing that steam distillation preceded by oxidation as separately applied steps cannot be effective. But the surprising results obtained by the conjoint action of steam and air in treating the fused mass is shown by the following:

Example 2.—Four thousand (4000) grams of the same raw material as in Example 1 were treated with 1200 grams of caustic soda in 6000 cc. of water, dehydrated and heated to fusion (320°-360° C.). A current of air saturated with water vapor was forced through the mass for 45 minutes while maintaining the temperature at 340° C. The current of air was stopped, and the mass was diluted with 6000 cc. of water, cooled, discharged and sprung with sulfuric acid solution; at the neutral point, the tar acid was decanted and distilled. Seventy (70) per cent of the tar acid was recovered, and the specific gravity at 20° C. was 1.007. The recovered product was free from higher alkyl phenols and impurities, and it compared very favorably in appearance and properties with tar acids fractions, collected within the boiling range of 220°-240° C., from high-temperature coal carbonization and having a specific gravity of 1.007 at 20° C.

The invention is further illustrated by the following:

Example 3.—Four thousand (4000) parts of a tar acids fraction, obtained by cracking petroleum and distilling between 230°-240° C., showed upon analysis a content of 0.08 per cent of sulfur and a specific gravity at 15.6° C. of 0.9945. This was dissolved in an aqueous solution containing 1200 parts of caustic soda whereby the phenol-

lates were formed; and the water solution of the phenolates, after separation by decantation, was concentrated by evaporating in a gas-heated stainless steel retort while being agitated with a scraping type agitator. When the molten mass reached a temperature of approximately 280° C., a current of air, which had previously been bubbled through water heated to 90° C., was blown through the molten mass until 10 to 15 cubic feet of air per gallon of tar acid used had passed through; during this operation the temperature of the molten mass was elevated to and maintained at 320 to 360° C. The amount of air and water used was determined by previous experimentation on a sample of the tar acids fraction.

During the air blowing step about 200 to 300 parts of a product having an offensive odor, a high sulfur content and a specific gravity of about 0.991 was carried off. The residue containing the phenolates was then dissolved in water, acidified and distilled to give a yield corresponding to 75 to 82 per cent of the original tar acids but with a specific gravity of 1.007, a sulfur content of 0.01 per cent and a decidedly phenolic odor. The product reacted favorably with formaldehyde and was comparable in specific gravity and otherwise to fractions of the same boiling range obtained from high temperature coal carbonization tar acids.

Example 4.—Four thousand (4000) parts of crude tar acids obtained by collecting the fraction distilling between 220°-250° C. of cracked petroleum products, was found by analysis to contain 0.69 per cent of sulfur, 0.3 per cent of nitrogen bases, and 3.1 per cent of oils and naphthalene; its specific gravity was 1.005. This was dissolved in an aqueous solution containing 1200 parts of caustic soda; and the water solution of the phenolates after separation by decantation was concentrated as in Example 3, and oxidized by passing therethrough 15 cubic feet of air per gallon of tar acids used, which air had previously been bubbled through water heated to 90° C.

During the blowing step, the oil carried off was collected by passing the gases through a cooling condenser; and the neutral oil and phenols present in the condensate had specific gravities of .987 and .998 respectively. The phenolates remaining in the retort were then dissolved in water, acidified to liberate the phenols, and the latter were then distilled to yield a phenol mixture of a specific gravity of 1.007, having a sulfur content of 0.042 per cent, and free from oil, naphthalene and nitrogen bases.

In the foregoing examples the concentration of the aqueous solution was in general about 60 per cent or more at the temperature of melting the mass, which temperature of course varies with the fraction selection for treatment and the ingredients constituting the fraction. The amount of air saturated with water vapor at about 90° C. required is determined by a preliminary trial on a sample; but it ranges generally from about 10 to 15 cubic feet for each gallon of crude tar acid fraction treated. By controlling the quantity of air and water vapor, the breaking of the side chain groups results largely in the formation of the useful phenol and methyl phenols from the higher alkyl phenols.

What is claimed is:

1. Process of treating a crude tar acid fraction including a phenol with a side chain group longer than the methyl group which comprises extracting the acid content by aqueous caustic soda and

separating the aqueous layer, heating the aqueous layer to substantially dehydrate and melt the mass, passing through the mass a current of air containing water vapor in amount to cause a breaking of the side chain group and to yield the sodium salt of a lower boiling phenol, and acidifying to free the lower boiling phenol.

2. In a process of treating a crude tar acid fraction obtained in the cracking of petroleum and containing a phenol with a side chain group longer than the methyl group, the steps which comprise extracting the acid content by aqueous caustic soda and separating the aqueous layer, heating the aqueous layer to substantially dehydrate and melt the mass, and passing through 15 the molten mass about ten to fifteen cubic feet

of air per gallon of the tar acid fraction after bubbling through water at about 90° C.

3. Process of treating in the form of the sodium salt a crude tar acid fraction including a phenol with a side chain longer than the methyl group which comprises heating the salt to a molten state, and passing through the melt a current of air containing water vapor.

4. Process of splitting off an alkyl group from a side chain on a phenol longer than the methyl group which comprises heating the sodium salt of the phenol to a molten state, and passing through the melt a current of air containing water vapor.

VITTORIO MOLINARI.
